UNITED STATES PATENT OFFICE.

WILLIAM T. BOOTH, OF BROOKLYN, NEW YORK, ASSIGNOR TO WESTERN ELECTRIC COMPANY, INCORPORATED, OF NEW YORK, N. Y., A CORPORATION OF NEW YORK.

VACUUM-TUBE SOCKET.

Application filed September 8, 1919. Serial No. 322,051.

To all whom it may concern:

Be it known that I, WILLIAM T. BOOTH, a citizen of the United States, residing at Brooklyn, in the county of Kings, State of New York, have invented certain new and useful Improvements in Vacuum-Tube Sockets, of which the following is a full, clear, concise, and exact description.

This invention relates to vacuum tubes and has particular reference to a new and improved form of socket structure to be used in vacuum tube sets in telegraphy and telephony.

An object is to provide an improved socket structure whereby a socket in use with one form of set and adapted to be used with one type of tube, cannot be used with any other type of tube while in that particular use.

Another object is to so construct the above-mentioned socket structure that the new element added, which constitutes the invention, may be readily adapted to or removed from the socket structure.

In the ordinary vacuum tube socket, the tube fits by means of a bayonet and lock-joint into the socket, the terminal plugs at its lower end slightly contacting with a plurality of terminal springs. In the ordinary tube, these terminal plugs on the base of the tube are definitely positioned angularly with respect to the bayonet pin also on the base, and similarly the terminal springs on the socket are definitely positioned angularly with respect to the bayonet lock so that when the tube is in position definite terminal springs will contact with definite terminal plugs on the tube. In order to adapt a socket for use only with one type of tube, this invention comprises the provision of a plate of insulating material which is interposed in a plane between the terminal springs and the plane of the base of the tube when in position in the socket. This plate is provided with suitable apertures which are definitely placed angularly with respect to the bayonet slot of the particular socket to which it is adapted, so that the terminal plugs only of the tube which is to be used with this socket, will

properly fit the aperture in the above-mentioned insulating plate and thereby pass therethrough to make contact with the terminal springs. This apertured plate may be an integral part of the socket base plate

or may be in the form of a separate piece as shown.

The invention is illustrated in the drawing, of which Fig. 1 shows a plan view of the socket structure; Fig. 2 shows a partial central longitudinal section of the socket and the associated tube in elevation taken on the line 1—1 of Fig. 1; Fig. 3 is an inverted plan view of the socket; and Fig. 4 is a partial elevation of the upper end of the socket.

As shown in the drawing, the socket structure comprises a base plate 1 having a wall portion 2 and a cylindrical portion 3. The socket portion 3 is provided with a bayonet slot 4 which is definitely located angularly with respect to a plurality of terminal springs 5, 6, 7 and 8 which are grouped centrally beneath the socket portion 3 and at one end are suitably fastened to an insulating block 9. Fastened to the plate 1 and beneath the same at a point below the lower opening of the socket portion is an insulating plate 10 which may, for instance, be composed of phenol-fibre. This plate is fastened in any suitable manner, such as by rivets 11, to the plate 1, and is provided with a single group of apertures 12, 13, 14 and 15. These apertures are oval in shape and are located substantially at equal distances from the center of the socket opening, their length along the circumference of a circle drawn through the mid-points being greater than their width. They are positioned approximately as shown in Fig. 1 over the socket terminals 5, 6, 7 and 8 so that the centers of the terminals 5, 6, 7 and 8 are placed toward one end of the apertures 12, 13, 14 and 15 in the direction of movement given to the vacuum tube when locking it in the socket. The vacuum tube comprises an evacuated envelope 16 and a base portion 17 provided at its lower end with electrode terminals of which two, 18 and 19 are shown. This tube is also provided with a bayonet pin 20 which is definitely located on the side of the tube with respect to the terminal electrodes.

The operation of the device is as follows:

Assuming that it is desired to use a particular type of tube with this socket structure, the position of the terminal springs 5, 6, 7 and 8, the electrode terminals of the tube, the apertures in the plate 10, and the posi-

tion of the bayonet slot 4 and the bayonet pin 20 are all definitely determined. It will be apparent that when the proper tube constructed as above is inserted in the socket and locked, its electrode terminals will register properly in the apertures of the phenol-fibre plate and contact with the springs of the socket.

On the other hand, if it is attempted to insert a tube into a socket not structurally adapted to be used therewith, then it will be equally apparent that because of the difference in the relative angular positions of the various parts mentioned above, the electrode terminals of the tube will not register with the apertures in the phenol-fibre plate, and therefore cannot pass therethrough to make contact with the socket springs.

20. What is claimed is:

1. A vacuum tube socket comprising a base plate having an aperture, a socket portion on said base plate in register with said aperture and adapted to receive a vacuum tube base, a plurality of contacts attached to said base plate below said socket portion, means on said socket portion adapted to cooperate with means on the base of a vacuum tube for locking it in said socket portion, and means interposed between said socket portion and said contacts, whereby only a vacuum tube base having a corresponding arrangement of terminal plugs with reference to said positioning means may be received within said socket portion.

2. A vacuum tube socket comprising a base plate having an aperture, a socket portion on said base plate in register with said aperture and adapted to receive a vacuum tube base, a plurality of contacts attached

to said base plate below said socket portion, means on said socket portion adapted to cooperate with means on the base of a vacuum tube for locking it in said socket, and an insulating member interposed between said socket portion and said contacts, said insulating member having apertures substantially in register with the ends of said contacts, said apertures being in a predetermined relation to said locking means whereby only a vacuum tube base having a similar arrangement of terminal plugs with reference to said locking means may be received within said socket portion.

3. A vacuum tube socket comprising a base plate having an aperture, a socket portion on said base plate in register with said aperture and adapted to receive a vacuum tube base, said socket portion having a bayonet slot adapted to receive the locking pin on the vacuum tube base, a plurality of contacts attached to said base below said socket portion in a predetermined relation to said bayonet slot, and an insulating member interposed between said socket portion and said contacts, said insulating member having apertures substantially in register with the ends of said contacts, said apertures being slightly larger than the terminals on the base of a vacuum tube to be received in said socket portion whereby only a vacuum tube base having an arrangement of terminal plugs with respect to the locking pin similar to the arrangement of said apertures may be received within said socket portion.

In witness whereof, I hereunto subscribe my name this 2nd day of September A. D. 1919.

WILLIAM T. BOOTH.
